(57) **CLAIM**

The ornamental design for an outside corner shelf, as shown and described.

DESCRIPTION

FIG. 1 is a perspective view of an outside corner shelf showing my new design;

FIG. 2 is a top plan view thereof;

FIG. 3 is a back elevation view thereof;

FIG. 4 is a front elevation view thereof; and,

FIG. 5 is a right side elevation view thereof;

FIG. 6 is a left side elevation view thereof;

FIG. 7 is a bottom plan view thereof;

FIG. 8 is an environmental perspective view thereof showing a corner bracket in an unattached position;

FIG. 9 is an environmental perspective view thereof showing a corner bracket in an attached position;

FIG. 10 is an environmental bottom perspective view thereof showing a corner bracket in an unattached position; and,

FIG. 11 is an environmental bottom perspective view thereof showing a corner bracket in an attached position.

The features shown in broken lines depict environmental subject matter only and form no part of the claimed design.

1 Claim, 8 Drawing Sheets
